Application December 12, 1956, Serial No. 627,890

8 Claims. (Cl. 271—89)

This invention relates to a vibratory apparatus and more particularly to a mechanical jogger for receiving and quickly aligning the edges of stacks of like sized sheet stock, such as paper sheets.

Joggers of present design employing vibrating table tops function satisfactorily on paper of relatively heavy stock but are employed with somewhat lesser success in a stock of extremely light weight, such as onion skin.

One of the objects of the present invention is a mechanical jogger providing a pulsating forced air which might be directed between the sheets of a random stacking of sheet stock to eliminate the previously encountered drag between the sheets being jogged.

A further object of the present invention is the provision of a jogger of improved design providing for ease of transportation and employment.

A further object of the present invention is the provision in a jogger of a source of forced air also functioning as the means for effecting the vibratory movement of the jogger table top.

Further objects and features of the invention will be readily apparent to those skilled in the art from the specification and appended drawings illustrating certain preferred embodiments in which:

Figure 1 is a perspective view of the jogger of the present invention illustrating the position of sheet stock to be jogged on the surface of the jogger.

Figure 2 is a sectional view taken along the lines II—II of Figure 1.

Figure 3 is a top plan view of the jogger with the cover removed and illustrating the exit port of the forced air fan in section.

Figure 4 is a sectional view taken along the lines IV—IV of Figure 3.

Figure 5 is a sectional view taken along the lines V—V of Figure 3.

The jogger 1 of the present invention constitutes a sheet metal box 2 having end, side and bottom walls and an open top. A vibrating surface 3 is provided above the box 2 upon which the jogging is accomplished. Resilient mounting feet 4 are provided for the box 2 along with handles 5 at each end of the box for ease of carrying and supporting. A snap switch 6 is provided in one side wall of the box 2 for the control of electrical energy to the power source for the jogger, all of which will be more fully described hereinafter.

At the upper surface of the box 2, the side and end walls are folded over to form a retaining lip at 7 supporting a plurality of cushion mounts 8 at positions around the interior of the box 2.

Within the box at each end thereof, a material of high mass 9 is provided adding stability and weight to the box of the jogger. This mass may be of any extremely dense material and, as shown in the drawings, may be of a molded concrete material.

Attached to the surface of the mass 9 are a pair of re-

2

silient springs 10 fixed in a manner to be securely held in the mass. As shown in the drawings, the mass being a molded concrete material, the springs 10 are molded into the mass and securely held upon setting of the concrete material. The opposite ends of the springs 10 are secured to a cross member 11 by individual screws 12 extending through the cross member 11 and through a rubber bushing 13 and into the interior of the spring 10 where a nut cooperates with the end of the screw and 10 against a retainer ring 14 in engagement with at least one loop of the springs 10.

The cross members 11 are secured by suitable screws 15 to the under surface of the jogger table top 3 at both sides and at each end of the box 2, and a resilient strip 16 is positioned between the upper surface of the cross member 11 and the under surface of the table 3. The previously mentioned bushings 8 are secured to the under surface of the table 3 as shown in Figure 4 by suitable screws 17 running into the under surface in a manner to ensure that the table does not bounce against the upper surface of the box 2 of the jogger.

Centrally disposed within the box 2 is a motor driven squirrel cage type fan having an involute tunnel through which forced air is passed to the under surface of the table top 3. The motor for the fan is shown at 21 and constitutes the conventional high speed, low voltage motor. The shaft 22 of the motor extends into the tunnel 23 of the fan and has secured thereto the squirrel cage rotor 24 having a plurality of fins 25 supported on a spider 26. The exit port of the fan tunnel 27 is secured by side channel brackets 28 to the under surface of the table top 3 by suitable screws 29 and is aligned with a hole 31 through the table surface 3 with a wire mesh 32 positioned between the under surface of the table 3 and the exit port of the fan.

The fan rotor 24 is adapted to provide pulsating air through the hole 31 by substantially closing a major number of the fins 25 leaving only a relatively few shown at 33 in a position to cause increased air movement as they pass through the involute fan tunnel. In this manner a continuous stream of air having pulses with each revolution of the fan rotor is provided through the opening 31 through the table top 3.

The fan is also provided with a means for producing vibratory motion in the jogger, this constituting unbalancing weights 34 secured by screws 35 to the fins at one side surface of the squirrel cage rotor. With each revolution of the fan rotor, a vibration will be produced due to the offset weights causing the entire fan housing to vibrate at the speed of revolution of the motor and this vibration will be transferred to the table 3 of the jogger through the connection of the fan to the under surface of the table top.

The operation of the jogger of the present invention should be readily apparent from the description of the parts constituting the assembly wherein it can be readily seen that with each revolution of the squirrel cage rotor of the fan pulses of air will be forced through the opening 31 in table surface 3 and the table surface will be vibrated in rhythm with the rotation of the offset weights 34 of the fan rotor. The mass 9 supported within the box 2 of the jogger will maintain the box itself in a relatively stable position and the springs 11 will permit the table surface to vibrate without transferring the vibratory motion into the box.

In employing the jogger to align a bundle or stack of random placed sheets, the sheets may be placed on the table surface 3 and passed across the opening 31 where the vibration of the table will cause the sheets to be urged into alignment and where the pulses of air passing

through the opening 31 will pass between the sheets in a rippling action to place a minute air cushion between adjoining sheets of the stack to eliminate friction between sheets and permit all sheets to drop into place in a stacking position. The jogging of even fine stock material may be accomplished with extreme ease in that all sheets of the stack will be separated by the forced air coming through the fan and each sheet may then independently drop into alignment with the level surface of the table top 3.

While a certain preferred embodiment of the invention has been specifically disclosed, it is understood that the invention is not limited thereto, as many variations will be readily apparent to those skilled in the art and the invention is to be given its broadest possible interpretation within the terms of the following claims.

What is claimed is:

1. A paper jogger for aligning individual sheets of randomly bundled paper comprising a box-like enclosure, a table top, means resiliently mounting said table top horizontally above and to said enclosure, an aperture extending vertically through said table top, means for producing pulsating air and vibratory motion secured to said table top and in alignment with said aperture whereby said sheets of randomly bundled paper being jogged on said jogger will be vibrated normal to said table top and separated from adjacent sheets by said pulsating air.

2. A jogging machine for aligning individual sheets of randomly bundled paper or the like, comprising a horizontal table for receiving the side edges of said sheets to be aligned, a resilient support for said table, means for producing a vibratory motion of said table upon said resilient supports, an aperture extending vertically through said table, and means for forcing a stream of air through said aperture to impinge said sheets along the plane thereof normal to said table.

3. A jogging machine for aligning individual sheets of randomly bundled paper or the like comprising a horizontal table for receiving said sheets to be aligned substantially vertically thereto, a resilient support for said table, means for producing a vibratory motion of said table upon said resilient supports, an aperture extending substantially vertically through said table, and means included in said vibratory motion producing means for forcing a stream of air substantially vertically through said aperture to impinge said sheets along the plane thereof.

4. A jogging machine for aligning individual sheets of randomly bundled paper or the like comprising a table for receiving the side edges of said sheets to be aligned, a resilient support for said table, means for producing a vibratory motion of said table upon said resilient supports, an aperture through said table, and means included in said vibratory motion producing means for forcing a stream of air through said aperture to impinge said sheets of randomly bundled paper at a side edge and along the plane thereof, said motion producing means being fixed to the under surface of said table.

5. A jogging machine for aligning sheets of paper or

the like comprising a table for receiving the sheets to be aligned, a resilient support for said table, a motor fixed to the under surface of said table, a fan fixed to said table and having a housing and a rotor rotatably supported therein, said rotor being driven by said motor, an eccentric weight fixed to said fan rotor for producing vibratory motion of said table about said resilient supports, an aperture through said table, said housing having an exit portal aligned with said aperture, and said rotor being operative to develop pulses of forced air through said housing and aperture to impinge upon said sheets along the plane thereof.

6. A jogging machine comprising an enclosure having a bottom and side walls and an open top, a mass supported in said enclosure on the bottom wall thereof, a table resiliently supported on said mass and extending above the side walls of said enclosure, a motor fixed to the under surface of said table, a fan having a housing and an internal, rotatably supported rotor member, means for driving said rotor by said motor, eccentric weights fixed to said rotor, an aperture through said table, said housing having an exit port being fixed to said table at the under surface thereof and aligned with said aperture, and said fan being rotatably driven by said motor to effect vibratory motion of said table and to produce pulses of air at said aperture, said pulses of air being directed through said aperture from below toward said sheets being jogged and along the plane of said sheets.

7. A jogging machine for aligning individual sheets of randomly bundled paper or the like, comprising a horizontal surface upon which the side edges of said sheets are placed whereby said sheets are vertically aligned to said horizontal surface, means for producing vibratory motion of said surface, and means for forcing a stream of air between individual sheets of said bundle at the side edges thereof and along the plane thereof vertical to said table.

8. The method of aligning individual sheets of randomly bundled paper or the like by jogging comprising the steps of supporting said bundle on an edge thereof against a support positioned substantially horizontally, vibrating said bundle of sheets at a high rate of vibrations per selected period, forcing air between said sheets while so bundled and along the plane of a face thereof to separate individual sheets within said bundle, and allowing each individual separated sheet to thereby align itself under its own weight against said support.
